PRESTON K. WOOD, OF LOS ANGELES, CALIFORNIA

PNEUMATIC LIFT PUMP

Application filed May 3, 1926. Serial No. 106,399.

This invention relates to air motive pumps and has for an object to provide an automatic mechanism intermittently admitting air or gaseous fluid under pressure to act on 5 and force up liquid in a well or other container.

An object is to provide a pneumatic lift system including a submersible, liquid check valve barrel and to provide a surface, control means for supplying controlled air pressure to dual air-ram chambers in the barrel.

Another object is to provide means for automatically throwing air exhausted from the air-ram chambers to either the low or 15 the high stages of an air compressor.

Further objects and advantages will be made manifest in the ensuing specification of apparatus embodying the improvements; it being understood that variations, modifications and adaptations may be resorted to 20 within the scope and spirit of the invention as it is here claimed.

Figure 1 is a general diagram of apparatus of the invention; parts being in section.

Figure 2 is a cross-section on line 2-2 of Fig. 1.

Figure 3 is a central, longitudinal section of the submersible pump barrel.

Figure 4 is a cross-section on line 4-4 of 30 Fig. 3.

Figure 5 is a cross-section on line 5-5 of Fig. 3.

Figure 6 is a cross-section on line 6-6 of Fig. 3.

Figure 7 is a central, longitudinal section of the auxiliary air control means regulating air to the compressor from the pump.

Figure 8 is a cross-section of a selective valve seat for changing effective pressure in 40 the control means of Fig. 7.

In this specification "motive-fluid" and "fluid" mean air or gas employed as the pressure medium or air-ram (or piston), and "liquid" means the substance to be forced out of the pump barrel by the fluid.

Submerged in a well or container C is a boot 2 having a set of down-closing check valves 3 in cages 4 under a retainer 5. The upper end of the boot 2 is attached to a hollow plug 6 from which extends upwardly a

nipple 7 surrounding a set of down-closing valves 8 in cages 9 at outlets 10 in the top of the plug 6. A retainer 10' holds down the cages 9 and limits movement of the valves 8.

Secured on the lower contracted end of the hollow plug 6 is a leg-pipe 12 which extends nearly to the retainer 5 and is open thereat for entrance of liquid entering by valves 3. Motive fluid air is led down to 60 plug 6 by a central feed tube 13 tapped into a distributing chamber 14 having cross-passageways 15 in arms in the chamber of the plug 6. In operation fluid pressure passes down the tube 13 and accumulates as a pneumatic piston ram or body on the liquid in the boot chamber 2^a so that the liquid is forced up into leg-pipe 12 and thence past valves 8. As a given degree of pressure is achieved a control means automatically reverses and the motive fluid is exhausted from boot 2 through tube 13. This occurs before the liquid falls below the bottom of leg-pipe 12 (see Fig. 3). When, or as, the pressure in boot 2 falls below static pressure against valves 3 liquid will rise past these valves.

Liquid passing, under motive pressure, up leg-pipe 12 flows up past valves 8 and thence up in a discharge joint 15' which is attached 80 to a valve housing 16 which closes the nipple 7. The housing 16 has a head 17 provided with a series of alternated inlet seats 18 for inlet valves 19 allowing inflow from outside ports 20, and outlet seats 21 for outlet valves 22. These valves 19-22 control flow to and from a pneumatic fluid-piston chamber surrounding the joint 15' and inside a shell section 23 secured to the head 17. This head 17 has a central passageway 17^a connecting with the chamber in nipple 7.

Section 23 is closed at the top by a hollow motive fluid drum 25 having ports 26 open to the section chamber 23 and having a 95 motive fluid supply (and exhaust) tube 27 which extends up along side tube 13 to the top of the well (in such an installation).

Hence, the pump, thus far described, consists of a barrel having an upper air cham- 100

ber 23 and a separate air chamber 2^a, independently supplied with, and exhausted of, motive fluid.

Liquid discharged past valves 22 enters 5 the common discharge passageway 17^a and flows from this to the joint 15' which outlets above the drum 25 into a reducer 30 connecting with a standpipe 31 running to the top of the well and enclosing the fluid 10 tubes 13—27.

The pump thus far described is in the general form of a barrel to be bodily lowered into a well or any container of liquid to be pumped.

15 *The surface equipment*

Motive or pressure fluid is compressed in a multistage compressor A having an air line B to a receiver C, forming a shock 20 absorber. From receiver C an air pipe 35 leads to an automatic air valve including a casing 36 having a bushing 37 in the bore of which is a reciprocating piston 38 having an upper port groove 39 and a lower port 25 groove 40.

The feed pipe 35 leads into an elongated passageway 41 having an upper cross-port 42 to register with piston port 39, when piston is up, and a lower cross-port 43 to 30 register with piston port 40, when the piston is down.

When the piston is up air flows from port 42 to a channel 42^a which leads to a top seat 45 for the piston. Seat 45 has a port 35 45^a closed by the upper convergent end of piston 38 so that a smaller or differential area of pressure is formed at the head of the seated piston.

When the piston is down motive air flows 40 from ports 43 and 40 to a channel 43^a which leads to a bottom-seat 46 for the lower tapered end, of the piston 38, which then closes a reduced area port 46^a, thus giving a differential action on the piston.

45 To channel 43^a is connected air tube 13, and to channel 42^a is connected air tube 27 (Fig. 1).

The length of the body of the piston valve 38, between ports 39 and 40 is such that 50 when the piston is up it covers a transfer port 44 from channel 42^a while the port 40 is uncovering a transfer-port 45 from channel 43^a. Ports 44—45 lead into a common duct 47 Figs. 2 and 7 having a pipe connection 47^a leading to the intake means of the compressor A. When the compressor is of multistage type I provide an auxiliary air line, intake control 50.

In Fig. 7 there is shown a means for controlling and regulating the time of shift of the piston.

This means includes a pair of variable-pressure, yieldable bolts 48—48^a which alternately snap into a recess 49 therefor in 65 and around the body of the piston when

the latter is shifted to its limits either way, endwise.

The auxiliary control includes a casing 50, bushed at 51, and having a piston valve 52 with a cross-port 53 which, in lower 70 position, registers with a diversion port 54 from a chamber 55 to an outlet 56 from which leads air-line 47^b to low pressure stage intake of the compressor A.

In its lower position piston 52 closes a 75 port-seat 57 of a diversion port 58 leading from chamber 55 to an outlet 59 from which an airline 60 leads to high stage intake of compressor A. The pipe 47^a leads to the common chamber 55.

80 Piston valve 52 is subjected to downward pressure of a spring 61 acting against air pressure on the lower end of the valve 52. A suitable regulating or friction device is provided to hold the valve in upper position 85 until a predetermined low pressure is present under the piston, at which time the master spring 61 will overcome action of the piston device and the valve will be thrust down. The device here includes a spring 62 90 acting against a ball-bolt 63 which will seat in a recess 64 in and around the piston valve. When air pressure is sufficient against the lower end of piston 52 this is thrust up to a stop collar 65 at which time the ball-bolt 95 63 snaps into its seat recess 64.

The operation

The two pump chambers 2^a and 23 are 100 designed to have the same water capacity and therefore the same volume and body of motive fluid can be rotatively circulated between the compressor and (alternately) the respective air spaces above the water in the chambers 2^a and 23. Hence while air pressure is building up in one chamber and acting to expel the water therefrom the other chamber is being exhausted down to atmospheric (or less if desired). In the position 105 of piston 38, Fig. 1, the piston has been forced up and is latched by bolt 48 Fig. 7, and is seated on seat 45 and is presenting a reduced head area to pressure in port 45^a while the lower end of the valve is fully exposed to lower pressure through open 110 port 46^a. In such position the compressor is receiving or pulling air from chamber 2^a, tube 13 to port 45, to duct 47, line 47^a, regulator 50, and by line 47^b or 60, and is returning it by line B, to receiver C, pipe 35, 115 channel 41, ports 39—42, thence to tube 27, and chamber 23.

The pressure in chamber 23 is driving liquid past valves 22 and joint 15' and discharge pipe 31 (valves 19 and 8 being closed). At this time air is escaping or being pulled from chamber 2^a to tube 13 and liquid is rising past valves 3, (Fig. 3).

As soon as pressure fluid, at port 45^a, is sufficient, on the reduced area of the piston 130

head, to overcome the pressure of bolt 48 the piston 38 will be forced downward. This action increases the head area of the piston as soon as it leaves the valve seat or 5 ring 45, and the increased effective area insures the full down shift of the piston until it bottoms on the differential port seat 46. When the shift occurs valve-port 40 is registered with port 43, escape 45 is closed, 10 escape port 44 is opened and port 42 is closed, and therefore, the flow cycle is reversed in tubes 13-27 from that indicated by the arrows (with tails) in Figs. 1 and 3. The reversing operation of the piston 15 valves 38 from either end position is exactly similar, and is automatic as long as the compressor is running. To nicely determine the degree of pressure needed at the differential area valve seats 45-46, a series 20 of these is provided the several seats having different sizes of ports, as indicated by the differential seat 45^b, Fig. 8. The pressure of the spring bolts 48-48^a may be readily varied by screws 48^b.

25 Should it happen that any material degree of pressure is present in the escape line 47^a (from the valve 38) it is desirable to divert this motive fluid to the high stage side of the compressor A. This is automatically accomplished by the diverting regulator or control device 50. By means of the spring 61; after it breaks holding action of friction ball 63 and the pressure effective on the exposed lower end of piston 30 52, the piston is held down and fluid passes ports 54-53-56 to the low stage line 47^b. But when master valve 38 shifts and throws the high pressure into line 47^a (from chamber 2^a or 23) then this pressure is instantly 40 effective on the unbalanced end of piston valve 52 and this overcomes spring 61 and port 59 is uncovered. When the piston 52 strikes stop 65 the friction ball 63 has snapped into recess 64 and while pressure 45 is falling in line 60 (to the high stage) the piston cannot shift until spring 61 overcomes the friction ball and remaining pressure on the lower end of the piston.

The advantage of this is to throw air to 50 high stage of compressor without passing it through the low stage, thus conserving power, and preventing overloading of the compressor motor.

What is claimed is:

51 1. A pump system having, in combination, a submersible barrel including independent, plural air chambers, liquid inlet valves for said chambers, liquid outlet valves for said chambers, a common liquid outlet conduit means for and interposed between the barrel chambers, and means for creating motive fluid pressure in the chambers to expel liquid therefrom, and for exhausting the motive fluid from the chambers in intermittent cycles, and including a valve having each end,

provided with differential area means for reaction of the motive fluid, motive fluid lines from said chambers to said valve ends, and means retarding shift of the valve and which is overcome by fluid pressure on said ends. 70

2. In a pneumatic-ram pump, a lower liquid inlet chamber and an upper liquid inlet chamber, a common liquid outlet nipple coaxially connecting the chambers, a discharge conduit leading axially from the nipple 75 through the upper chamber, valved outlets from the chambers to the nipple, and separate air feeders to the chambers, one of which extends axially to the nipple.

3. In a pneumatic-ram pump, a lower liquid chamber and an upper liquid chamber each having liquid inlet means, a common liquid outlet nipple connecting the chambers, a discharge conduit leading from the nipple, valved outlets from the chambers to the 85 nipple, and separate air feeders to the chambers; said feeders being enclosed in the conduit.

4. In a pneumatic-ram pump, an upper liquid intake chamber, a lower liquid intake 90 chamber, an intermediate nipple connecting said chambers for common discharge, valves for discharge flow from the chambers to the nipple, a discharge conduit having a part extending down coaxially through the upper 95 chamber and connecting to the nipple, an air distributing head below the nipple and having a coaxial leg-pipe for discharge from the lower chamber to the nipple, and air feeders to the chambers. 100

5. An elastic fluid motive system, for pumping a liquid, including a submersible pump having a discharge means for liquid superposed fluid chambers each having liquid inlet valve means and outlet valve means, 105 independent means for leading motive fluid to and from each chamber, means operative by the motive fluid for controlling the action of the motive fluid in said chambers, and a retaining adjustable spring device governing 110 the control means.

6. An elastic fluid motive system, for pumping a liquid, including a set of upper and lower air chambers, a set of liquid inlet and outlet valves for each chamber, a common liquid discharge means from the chambers, means therein to supply motive fluid to said chambers, and a means operative by the motive fluid for controlling action of the fluid on liquid in chambers, said control 120 means including a piston valve and a chamber therefor having connection with the fluid supply means for fluid action on opposite ends of the piston; said piston having a body groove, and a spring device engaging the 125 piston to restrain it and seating in the groove.

7. An elastic fluid motive system, for pumping a liquid, including a set of superposed, associated air chambers, a set of liq- 130

- uid inlet and outlet valves for each chamber, a common liquid discharge means from the chambers, separate motive fluid conduits for the chambers, and a means operative by 5 the motive fluid for controlling action of the fluid on liquid in said chambers; said control means providing for supply of motive fluid to said chambers and its flow therefrom said control means including a piston 10 and its chamber, said conduits connected to the chamber for exhaust thereto and supply therefrom and for fluid action on the ends of the piston.
8. An elastic fluid motive system, for 15 pumping a liquid, including dual air chambers, a set of liquid inlet and outlet valves for each chamber, a common liquid discharge means from the chambers, separate motive fluid conduits to the chambers, a means operative by 20 the motive fluid for controlling action of the fluid on liquid in chambers, and compressing and exhausting means, for the motive fluid, connected to the control means, said control means including a piston whose 25 ends are exposed to pressure fluid in the said conduits whereby to be shifted to and fro to reverse fluid flow, said control means including a retarded action piston valve having differential area ends for cumulative action 30 of motive fluid to overcome retardation and effect a full shift.
9. In a pneumatic pump, in combination, an upper air chamber and a lower air chamber, a coupling means connecting the chambers and having upper and lower sets of 35 valves opening thereto from each chamber, and a discharge pipe leading from the coupling chamber up through the upper chamber, and liquid inlet valves at the bottoms 40 of the air chambers.
10. In a pneumatic pump, in combination, an upper air chamber and a lower air chamber, a coupling connecting the chambers and having valves opening thereto from each 45 chamber, and a discharge pipe leading from the coupling chamber up through the upper chamber, liquid inlet valves at the bottoms of the air chambers, the chambers having each, a pipe for the alternate supply and eduction 50 of motive fluid, and control means including a piston valve which is operatively controlled by fluid pressure in the said supply and eduction pipes and a pressure supply line, said control means being interposed between 55 said line and the pipes to control pressure fluid flow to the air chambers.
11. In an automatic pneumatic pump, a plurality of sunken air chambers having 60 liquid inlets, a master piston valve and its casing, a fluid supply passage to said casing, fluid conduits in the ends of the casing to the piston valve ends, independent pipe lines from the conduits to respective air 65 chambers for supply and eduction of fluid,
- and means reacting on the piston valve to retain it momentarily while air pressure is accumulating on one or the other ends of the piston valve from one air chamber, said piston valve having differential end areas 70 for reaction of the fluid pressure.
